COUPLER FOR ELECTRIC MUSICAL INSTRUMENTS.

1,191,482.

Specification of Letters Patent.

Patented July 18, 1916.

Application filed July 20, 1912. Serial No. 710,637.

To all whom it may concern:

Be it known that we, MELVIN L. SEVERY, of Arlington Heights, in the county of Middlesex and Commonwealth of Massachusetts, and GEORGE B. SINCLAIR, of Georgetown, in the county of Sagadahoc and State of Maine, both citizens of the United States, have invented certain new and useful Improvements in Couplers for Electric Musical Instruments, of which the following is a full and exact description.

This invention pertains primarily to the type of electric musical instruments wherein magnetically attractive sonorous bodies, as strings and bars, are vibrated by means of electromagnets having suitably timed electric pulsations delivered thereto.

It is obvious that this instrument lends itself readily to mechanical manipulation by means of traveling perforated music rolls, and the like, as found in the mechanical players at present on the market, most of which operate to press the keys of the ordinary keyboard. Any means, however, of opening and closing the appropriate electrical circuits, whether through the operation of the keys of the keyboard or otherwise, would come well within the scope of our invention, and whenever, therefore, we herein refer to "keys", we wish to be understood to include within that term any mechanism operating to produce the results for which said keys are designed, as it is manifest that the various circuits of this instrument could be opened and closed mechanically, either with or without the use of a keyboard. We do not, therefore, limit ourselves in the specification and claims to an instrument operated only by the usual pressure of the keys of a keyboard, but desire to include any means by which this instrument may be operated by a mechanical or human player.

Among the objects of this invention are, first, the construction of a simplified electrically operated note coupler for instruments of the kind above set forth, as well as for instruments of other types; second, the construction of means for automatically withdrawing the dampers from several sonorous bodies of like name when any one thereof is vibrated, and of other details of construction hereinafter set forth.

In the drawings forming part of this specification, Figure 1 is a perspective diagrammatic view of parts of an electric musical

instrument embodying our improvements. Fig. 2 is a front view of a part of the coupler bar and the action contacts. Fig. 3 is a cross section on the line X—X in Fig. 2.

In said drawings and in the following description, we set forth our invention as specifically adapted for coupling octaves, but it is evidently equally applicable for coupling notes of any desired musical interval.

The reference numeral 1 designates one of the sonorous bodies, the same being either a single string, or a group of two or three strings tuned in unison in the usual manner. Each string or group of strings is vibrated by means of an electromagnet 2, to which properly timed electric pulsations are delivered by a make-and-break device consisting of disks or rings 3 and coöperating brushes 4, receiving current from a suitable source 5. Said disks or rings having suitably disposed teeth and insulation, and being rotated with absolute uniformity, the pulsations thereby delivered to the associated electromagnets will cause the vibration of the strings 1, whenever the circuits are closed, either by the depression of the keys or in other ways.

Preferably each key 6 is connected with a brush 7 through a sticker 9 and lever extension 10, as shown in Fig. 3, so that the depression of the outer extremity of the key elevates its inner end, and with it the sticker, lever extension and brush; said brush being thereby caused to pass from the dead surface 11 of the contact rail to the contacts above the same. When a brush is resting against said dead surface 11, no current can pass and the associated string 1 is dumb. When a brush reaches the first contact 12, current passes from the source 5 to a wire 13 common to all the brushes, and thence to the brush referred to, then through said contact 12, resistance 14 and suitable connection to the T-shaped contact 15, from the latter through the wire 16 to the associated electromagnet 2, from the electromagnet through the wire 17 to the brush 4, disk 3, and a connection 19 back to said source; the passage of the current through the make-and-break device giving it the proper pulsatory character. A further elevation of the brush 7 brings it into touch with said T-shaped contact 15 so that the current no longer traverses the resistance 14 but proceeds with full strength to the associated

electromagnet, and so causes the vibration of the string more loudly. It is necessary simultaneously with this to remove the damper 20 from said string. To do this, each 5 wire 16 is connected by a wire 21 to an electromagnet 22 whose armature 23 is adapted for thus actuating the damper, and said electromagnets 22 are joined by a wire or wires 24 to said source direct, and hence are 10 not subject to the pulsations delivered to the magnets 2.

Although we have spoken of the resistance elements 14 as serving to give a primary softer action, yet this is not the most important 15 function performed thereby, inasmuch as the greatest value thereof is the reduction of sparking, both when the current is switched on and when it is switched off, over what it would be did the brush 7 pass direct 20 to the T-shaped contact 15.

The note coupling portion of our invention is constructed as follows: A short distance above the contact rail 25 (see Fig. 2) is the coupler rail 26 connected therewith by 25 two or three leaf springs 27, one end of each spring being rigidly fastened to the contact rail, and the other end to the coupler bar; said springs being adapted for resiliently holding said bar in its lower position. Felt 30 pads 29 serve to prevent jar when said coupler bar is dropped. This coupler bar carries a number of brushes 30 arranged in pairs, the lower ends of each pair being normally in touch with the upper part of the 35 T-contact 15 of one of the notes. Immediately above each contact 15 are two contacts 31 insulated from each other and from the contact 15, but one wired to a contact 15 an octave above, the other to a contact 15 an 40 octave below. By having the contacts 31 out of touch with each other, when a brush 7 is brought into touch with the contact 15 while the coupler bar or rail 26 is in its elevated position, current will pass to brushes 45 30 an octave above and an octave below. The circuits of the three coupled notes will therefore be as follows: from the source 5 to the operated brush 7 and thence through the contact 15, wire 16, electromagnet 2, wire 50 17, make-and-break devices 4, 3 and wire 19 back to said source, as already described. Simultaneously therewith, the current will pass from said brush 7, through the contacts 32, wires 33, brushes 30, contacts 31, wires 34 55 to contacts 15 an octave below and an octave above, thence through wires 16 to the associated electromagnets 2, and back to the source in the same way as just described. The coupled current cannot pass farther 60 than an octave each way because the brushes 7 at such octaves are not elevated and do not, therefore, bridge the contacts 32 and 15. Simultaneously with the energizing of the electromagnets 2 an octave above and an 65 octave below the operated key, and the conse-

quent vibration of the three sonorous bodies, non-pulsatory current will pass to the three associated electro-magnets 22 in the manner already described, and their dampers will be withdrawn from the said three sonorous 70 bodies. When the coupler rail 26 is permitted to return to its seats 29, the brushes 30 return into touch with the contacts 15, and all the coupling circuits are broken. For the operation of said coupler rail, we 75 prefer to employ a rocker shaft 35 provided with two or three fingers 36 adapted to engage an equal number of elbows 37 attached to said rail. By rocking said shaft in any suitable way, as by pedal-controlled reciprocating rod 39 pressed up against an arm 40 rigid with said shaft, said rail is readily raised and lowered at will.

What we claim as our invention and for which we desire Letters Patent is as follows, 85 to wit:

1. In combination with a plurality of sonorous bodies tuned in musical relation to one another, electromagnets for causing vibration of said bodies; dampers for said bodies; electromagnets for withdrawing said dampers; electrical means, including a circuit-closer, for independently energizing the electromagnets associated with each sonorous body and with the damper thereof, 95 pulsation-producing devices, one in circuit with each circuit-closer, for imparting timed electric pulsations to the vibration-producing magnets; and electrical connections between the actuating device of a selected body and of other sonorous bodies bearing predetermined musical relation thereto, for causing the simultaneous retraction of the several dampers and energizing of the several magnets of the selected and related sonorous 100 bodies through the action of the single selected actuating device.

2. The combination with tuned sonorous bodies and electromagnetic means for their actuation, of pulsation-producing devices 110 for imparting timed electric pulsations to said magnets; dampers for the respective bodies; electrically-operated means for withdrawing the respective dampers; and means common to the actuating devices of a selected sonorous body and of another sonorous body bearing predetermined musical relation thereto, and common to their damper-withdrawing means, whereby the closing of the energizing circuit of the magnets of a selected sonorous body effects the simultaneous closing of the energizing circuit of the related sonorous body and of its damper-withdrawing devices.

3. The combination with tuned sonorous bodies and electromagnetic means for independently actuating the same, of pulsation-producing devices for imparting timed electric pulsations to said means; dampers for the respective bodies; electrically-operated 125

means for withdrawing said dampers from the actuated sonorous bodies; and electrical connections between the actuating devices of a plurality of the sonorous bodies bearing 5 predetermined musical relation, and between their damper-withdrawing devices, whereby operation of the actuating device of one of said sonorous bodies effects the simultaneous withdrawal of the several 10 dampers, and the simultaneous actuation of said bodies.

4. The combination with tuned sonorous bodies, of electric means for their actuation including a circuit closer for each; pulsation-producing devices, one in circuit with each circuit-closer, for imparting timed electric pulsations to said actuating means; an electrically-operated damper mechanism for causing the actuation of the dampers of a 20 limited number of bodies bearing a predetermined musical relationship to one another, when a selected body is sounded; and means for simultaneously delivering current to the damper mechanisms of the several 25 bodies sounded when the circuit closer of the actuating device of the selected body is moved to closed position.

5. The combination with tuned sonorous bodies, of means for their actuation comprising an electromagnet, an electric circuit and circuit-closer for each sonorous body; pulsation-producing devices, one in circuit with each circuit-closer, for imparting timed electric pulsations to said magnets; 30 a damper for each of said bodies; an electromagnet for each damper serving, when energized, to withdraw the same, each damper magnet being connected in parallel to the actuating magnet of the body with 35 which such damper is associated; and means for connecting in circuit the actuating electromagnets of a plurality of the sonorous bodies bearing predetermined musical relation to one another, whereby the closing of 40 the circuit of a single selected sonorous body effects the closing of the circuits of the actuating and damper magnets of such related bodies.

6. A musical instrument comprising 45 tuned sonorous bodies; electromagnets for vibrating said bodies; means for delivering correctly timed electric impulses to said electromagnets; keys controlling said means; dampers for the sonorous bodies; electromagnets for withdrawing said dampers; and means operative at will for causing each key upon its depression so to distribute the current as to sound not only the note normally associated with it but also that an 50 octave away, and to withdraw the dampers of both note-producing bodies.

7. A musical instrument comprising tuned sonorous bodies; electromagnets for vibrating said bodies; means for delivering correctly timed electric impulses to said electro-

magnets; keys controlling said means; dampers for the sonorous bodies; electromagnets for withdrawing said dampers; and means operative at will for causing each key upon its depression so to distribute the current as to sound not only the sonorous body usually associated with it but also that an octave above and that an octave below, and to withdraw the dampers of the several bodies sounded.

8. A musical instrument comprising tuned sonorous bodies; electromagnets for vibrating said bodies; means, including circuits, for delivering correctly timed electric impulses to said electromagnets; dampers for said bodies; electromagnets for withdrawing said dampers; keys controlling the means for delivering timed electric impulses to the electromagnets of the sonorous bodies and of their dampers; and a single coupler rail for switching into the circuit of any depressed key the circuit of an electromagnet vibrating a sonorous body an octave higher and also that of a sonorous body an octave lower than the body associated with such depressed key, together with the electromagnets of the dampers associated with the several sonorous bodies sounded.

9. A musical instrument, comprising tuned sonorous bodies, electromagnets for their vibration, means including keys, contacts and brushes for delivering timed electric impulses to said electromagnets, each key controlling a brush movable into engagement with three contacts, one of said contacts being connected to the electromagnet actuating the sonorous body normally associated with said key, and each one of the other two said contacts being connected with a movable brush, each said brush being adapted to be put into engagement with a contact, the contact for one of said brushes being in electrical connection with the magnet actuating the sonorous body an octave above that normally associated with said key, and the contact for the other brush being in electrical connection with the electromagnet actuating the sonorous body an octave below that normally associated with said key, and means for bringing said key-controlled brush and the pair of brushes associated therewith into direct electrical connection with each other and with the aforesaid contact connected to the magnet actuating the sonorous body normally associated with said key.

10. A musical instrument, comprising tuned sonorous bodies, electromagnets for their vibration, means including keys, contacts and brushes for delivering timed electric impulses to said electromagnets, each key controlling a brush movable into engagement with three contacts, one of said contacts being connected to the electromagnet actuating the sonorous body normally asso-

- ciated with said key, and each of the other two said contacts being connected with a movable brush, each said brush being adapted to be put into engagement with a contact, the contact for one of said brushes being in electrical connection with the magnet actuating the sonorous body an octave above that normally associated with said key, and the contact for the other brush being in electrical connection with the electromagnet actuating the sonorous body an octave below that normally associated with said key, and means operative at will for putting said contacts respectively electrically connected to the electromagnet associated with the sonorous body an octave above and to the electromagnet associated with the sonorous body an octave below the sonorous body normally associated with said key out of touch with their associated contacting brushes.
11. A musical instrument, comprising tuned sonorous bodies, electromagnets for their vibration, means including keys, contacts and brushes for delivering timed electric impulses to a plurality of said electromagnets simultaneously upon the operation of a single key, each key controlling a brush movable into engagement with three contacts, one of said contacts being connected to the electromagnet actuating the sonorous body normally associated with said key and each one of the other two said contacts being connected with a movable brush, each said brush being adapted to be put into engagement with a contact, the contact for one of said brushes being in electrical connection with the magnet actuating the sonorous body an octave above that normally associated with said key, and the contact for the other brush being in electrical connection with the electromagnet actuating the sonorous body an octave below that normally associated with said key, and means for bringing said key-controlled brush and the pair of brushes associated therewith into direct electrical connection with each other and with the aforesaid contact connected to the magnet actuating the sonorous body normally associated with said key.
12. A musical instrument, comprising tuned sonorous bodies, electromagnets for their vibration, and means including keys, contacts and brushes for delivering timed electric impulses to a plurality of said electromagnets simultaneously upon the operation of a single key, the contacts associated with each of said keys being five in number, three of which contacts are in a group adapted to be engaged by the brush controlled by its key, one contact in this group being T-shaped with the other two of the group located beneath its branches but out of circuit therewith, the other two contacts of said five

being positioned immediately above the T-shaped contact but normally out of circuit therewith, and said means also including a vertically movable horizontal bar carrying brushes in pairs, each pair being normally out of engagement with the last-mentioned two contacts of each five, said bar having means for raising it to put its brushes into touch with the last-mentioned two said contacts.

13. A musical instrument comprising tuned sonorous bodies; electromagnets for their vibration; dampers for said bodies; electromagnets for withdrawing said dampers; and means including keys, contacts and brushes, for delivering timed electric impulses to three of said electromagnets simultaneously, and for delivering electric current simultaneously to the damper-controlling magnets upon the operation of a single one of said keys, the three vibration-effecting electromagnets embracing in each case the electromagnet associated with said key and the two an octave therefrom.

14. In a musical instrument, the combination of sonorous bodies, electromagnetic means including circuits, for the vibration of said bodies, and means for coupling certain of said circuits comprising a contact rail, a coupler rail parallel therewith, and leaf springs fastened at their ends to said rails, one end of each spring to one rail and the other end to the other rail.

15. In a musical instrument, the combination of sonorous bodies, electromagnetic means including circuits, for the vibration of said bodies, and means for coupling certain of said circuits comprising a contact rail, a coupler rail parallel therewith, brushes carried by the coupler rail in touch with said contact rail, a rocker shaft, and fingers rigid therewith adapted to raise said coupler bar when the rocker shaft is partially turned.

16. In a musical instrument, the combination of sonorous bodies, electromagnetic means including circuits, for the vibration of said bodies, and means for coupling certain of said circuits comprising a contact rail, a coupler rail parallel therewith, brushes carried by the coupler rail in touch with contacts of said contact rail, a rocker shaft, fingers rigid therewith, and elbows rigid with the coupler rail engaged by said fingers.

In testimony that we claim the foregoing invention, we have hereunto set our hands this 16th day of July, 1912.

MELVIN L. SEVERY.
GEORGE B. SINCLAIR.
